UNITED STATES PATENT OFFICE.

WILLIS WALKER, OF SEDALIA, COLORADO.

PUZZLE.

No. 907,203.

Specification of Letters Patent. Patented Dec. 22, 1908.

Application filed September 20, 1907. Serial No. 393,854.

To all whom it may concern:

Be it known that I, WILLIS WALKER, a citizen of the United States, residing at Sedalia, in the county of Douglas and State of Colorado, have invented a new and useful 5 Puzzle, of which the following is a specification.

This invention relates to puzzles and more particularly to geometrical devices of this 10 character made up of a plurality of angular blocks of different contours designed, if assembled in a particular manner, to constitute a cube capable of fitting snugly within a suitable retaining case when not in use. 15 The blocks, however, are so shaped that when they are separated they can, by the proper placing thereof, be assembled to form a single rectangular figure of the thickness of one block. This arrangement of the blocks, 20 however, will be found extremely difficult by persons inexperienced in the use thereof.

With these and other objects in view the invention consists of certain novel features of construction and combinations of parts 25 which will be hereinafter more fully described and pointed out in the claim.

In the accompanying drawings is shown the preferred form of the invention.

In said drawings: Figure 1 is a perspective 30 view showing the blocks assembled to form a cube. Fig. 2 is a perspective view of one set of blocks spaced apart. Fig. 3 is a plan view showing the blocks assembled to form a rectangular figure.

35 By referring to the drawings it will be noted that the puzzle consists of preferably five sets of blocks each set consisting of a right-angle-triangular member 9 and a trapezoidal member 8 so assembled that when the 40 hypotenuse 7 of the member 9 is placed against the diagonal face 10 of the member 8 a perfect rectangular figure will be formed. The smaller base of each member 9 is of the 45 same size as the smallest side of the trapezoidal block.

In assembling the several parts difficulty will at first be experienced in determining the contour of the middle or basic portion of the figure to be produced. This difficulty is increased because only two forms of blocks are 50 employed, to wit, triangular blocks 9 and trapezoidal blocks 8. In order to assemble the several blocks one member 8 and one member 9 are assembled so as to form a rectangle, after which one of the trapezoidal sections 8 is placed against each side of the rectangle and with its diagonal face 10 outermost. Triangular spaces will thus be formed at the corners of the middle rectangular figure and these spaces will be of the same 55 proportions as the triangular blocks 9 which can thus be seated therein and the hypotenuse of each of the blocks 9 will thus aline with the diagonal face 10 of one of the adjoining blocks 8. When the blocks are not 60 in use the two sets can be assembled in pairs so as to form rectangles of uniform proportions and which can be superposed as indicated in Fig. 1 and placed within a suitable 65 box.

70 What is claimed is:

A puzzle comprising a cube consisting of five layers of blocks each layer comprising a trapezoidal block and a right angle triangular block, the smaller base of the triangular 75 block being of the same length as the smallest side of the trapezoidal block, said blocks being designed when assembled in a predetermined manner to constitute a square having an area five times greater than the area 80 of one face of the cube, the thickness of each block being one-fifth of the thickness of the cube.

In testimony that I claim the foregoing as my own, I have hereto affixed my signature 85 in the presence of two witnesses.

WILLIS WALKER.
